WINDOW STAY

Carl Olson, Minneapolis, Minn., assignor to
Wright Products, Inc., Minneapolis, Minn., a
corporation of Minnesota

Application November 20, 1940, Serial No. 366,355

4 Claims. (Cl. 292—263)

This invention relates generally to improvements in window hardware and more particularly to the stays or adjusters used for holding storm windows and screens in adjusted positions in the window frames.

In the use of such devices it is obvious that in replacing the storm windows with screens, and vice versa, as the seasons change, some convenient means must be provided for disconnecting the stays or adjusters from either the window frame or the storm window, or screen, as the case may be. In some instances it is best to disconnect from the storm window or screen leaving the stay on the window frame and in other cases it may be desirable to disconnect at the window frame so that the stay will remain with the storm window for storing. The latter is true of course where either no screens are used or where it may not be desired to use a stay with the screen.

The primary object of my invention is to provide a window stay having means for convenient disconnection from the window frame without the use of any tools and to provide a stay having means for as convenient disconnection from the storm window or screen. Another object is to provide window hardware of this kind in simple, durable, inexpensive and neat form.

These and other more detailed and specific objects will be disclosed in the course of the following specification, reference being had to the accompanying drawings, in which—

Fig. 1 is a side elevation of my stay or adjuster showing the same as mounted on a window frame and storm window (only portions of which are shown) and with the storm window swung outward some distance from the frame.

Fig. 2 is a plan view of the stay alone.

Fig. 3 is an elevational view of the frame mounting device alone.

Fig. 4 is a vertical section along the line 4—4 in Fig. 1.

Fig. 5 is an inside elevation of the mounting device of Fig. 3.

Fig. 6 is a view similar to Fig. 1 but showing a modified form of my stay or adjuster.

Fig. 7 is a plan view of the stay of Fig. 6.

Fig. 8 is an enlarged fragmentary section along the line 8—8 in Fig. 6.

Fig. 9 is a fragmentary side elevation of one end of the stay of Fig. 6 showing the locking member swung to a position for disconnecting the stay from the storm window or screen.

Referring now more particularly and by ref-

erence characters to the drawings, I here have shown a window stay designed to connect a lower portion of a closure member such as a storm window or screen A to the window frame B. A stay may be used at each side of the window as will be evident, but in this description only one stay for one side of the window will be set forth in detail since such minor changes as required for right and left hand use will be apparent.

As shown in Figs. 1 through 5 the stay, designated generally at C, comprises an articulated foldable brace made up of inner and outer arms or members 10 and 11 pivotally connected at meeting ends by a pivot bolt 12. The outer end of the arm 11 is also pivotally connected by a pin 13 to a bracket 14 which may be secured, as by screws 15, to the storm window (or screen) A and which has an inwardly turned ear 16 for the pin 13.

The fastening for the inner arm or member 10 comprises a plate or mounting 17 having screw holes 18 at upper and lower ends through which screws 19 may be passed for securing it to the inside of the window frame B. At substantially a medial portion the plate 17 has a keyhole-shaped opening or slot having a relatively narrow lower end 20 and larger upper end 21. A pin 22 is fixed to the extremity of the inner brace arm 10 and is of such diameter that it may be entered easily into the large upper end 21 of the slot, while the pin has a diametrical groove 23 which may then be slipped downwardly over the vertical margins of the narrow end 20 of the slot to pivotally engage the same. In this position a head portion 24 of the pin fits within, or on the side of, the plate 17 toward the frame B, and to provide clearance the plate is preferably pressed to the dish-shape shown so as to provide a recess 25 to clear this head 24 and other parts.

A flat spring 26, constituting a keeper or latch member, is riveted or otherwise fastened at 27 to the inner side of the plate 17 and extends upwardly within the slot in the plate, the upper end 45 of the spring being bent outward at 28 through the upper end of the slot in the plate and then turned upwardly in the form of a finger piece or ear 29 which is serrated or knurled as shown. A lug 30 is punched from the spring 26 in such position that it will, as shown in Fig. 4, engage the upper side of the head 24 of the pin 22 when the same is entered in the slot.

In operation the bracket 14 and plate 17 are secured to the storm window A and frame B, respectively, as described and shown and when the

storm window is put up the stay C is connected by inserting the pin 22 in the upper end 21 of the slot in plate 17 and then forcing it downwardly until the groove 23 engages lower margins of the slot. In this operation the pin 22 cams over the lug 30 forcing the spring 26 inwardly as the pin passes and then, as the pin clears the lug 30 the spring again returns outwardly so that the lug 30 prevents upward displacement of the pin and disconnection of the stay. Of course the stay may be readily disconnected from the plate 17, when the storm window is taken down, simply by pressing upon the finger piece 29 until the pin 22 may clear the lug 30 and then lifting the pin from the slot in the plate.

When thus mounted the stay C will operate in usual fashion, unfolding and extending outward as the storm window is swung outward to hold it in this position and jackknifing to a folded position when the storm window is closed tight against the window frame.

The lateral margins of the spring 26 may be turned or rolled as shown at 31 in order to afford rigidity at this part of the spring. In any event the spring is arranged and adapted to engage the head portion 24 of the pin 22 as the same rests in the slot in plate 17. Added friction is thus provided and rattling of the parts prevented.

In the folding and unfolding operation of the stay the arms or members 10 and 11 of course pivot about all three pivots 12, 13, and 22, but the center joint or pivot 12 is made adjustable in tension or resistance so that the stay may have sufficient rigidity to hold the storm window in adjusted position. The inner arm 10 is a single, flat strip of material having a pressed longitudinally extending stiffening rib 32 but the outer arm 11 has an upper edge turned over at right angles in the form of a flange 33. The meeting ends of the arms 10 and 11 overlap and are apertured to receive the bolt 12, and, at each side of the end of the inner arm, hard rubber, fibre, Bakelite, or similar washers 34 are placed on the bolt. The head of the bolt, having a squared shank 35, is placed through the squared hole in a washer 36 and this washer is locked against rotation relative to the member 10 by a lug 37 on the washer engaged with a notch 38 in the flange 33. The nut 39 is placed on the inner end of the bolt and when drawn up tight against the arm 11 will cause pressure against the washers 34 to provide conveniently adjustable resistance to pivoting movement at this joint. Since the bolt 12, washer 36, arm 11 and nut 39 all must turn as a unit, there is no tendency for the nut to loosen as will be evident. The notch 38 is deep enough to provide sufficient play for the washer 36 in making this adjustment.

A radially extended stop shoulder 40 on the member 10 engages the end 41 of the flange 33 to limit unfolding movement of the stay and prevents the arms 10 and 11 from reaching the aligned position from which they might fold in the direction (downward) opposite to that desired.

A fibre, plastic, or Bakelite washer 42 may be arranged between the outer end of member 11 and the bracket ear 16 to provide stiffness or resistance at this point also.

Referring to Figs. 6 through 9, I have shown therein a modification of my stay or adjuster represented generally at C' and shown as connected between a storm window (or screen) A' and window frame B'. This stay C' comprises

inner and outer arms or members 43 and 44 pivotally joined at meeting ends by a bolt 45. In this case, however, the inner arm 44 is pivoted, as by a rivet 46, to a bracket 47 which may be secured by screws 48 to the window frame B' to provide a mounting for the stay, the said bracket being pressed to cause its center portion 49 to stand outward from the frame and a friction washer 50 being provided between the arm and bracket to prevent looseness at this joint.

The outer arm 44 carries a rigidly mounted pivot pin 51 near its outer extremity adapted to be pivotally received in the apertured ear 52 of a bracket 53 which is secured by screws 54 to the

15 storm window A'. A latch member 55 is pivotally mounted by a rivet or pin 56 to the arm 44 and at one end 57 this latch member is offset at 58 from the adjacent surface of the arm a distance sufficient to just clear the bracket ear 20 52. This end 57 is rounded off at its extremity 59 on a radius centered on the axis of the rivet 56 and is so dimensioned that it will enter a groove or slot 60 cut in the adjacent side of the pin 51 in which position the latch member will 25 obviously prevent the disengagement of the pin from the bracket 53. The other end of the latch member 55 is folded and creased to provide an operating portion 61 and the arm 44 has a boss 62 pressed inward in position to be engaged by 30 the parallel folded margins 63 of this end of the latch member.

In operation the stay is mounted as described by fastening the brackets 47 and 53 to the window frame and storm window and then, as the 35 storm window is put up, the pin 51 on the outer arm 44 is inserted through the bracket ear 52 and the latch member turned to a position parallel with the arm so that its end 57 enters the groove 60 and overlies the ear 52 to maintain 40 the pivot connection at this end. The stay will then fold or unfold as required to open or close the storm window. When the storm window is to be taken down the latch member 55 is swung aside to the position shown in Fig. 9 where its 45 end 57 clears the ear 52 to allow the pin 51 to be withdrawn therefrom and the window may then be removed and replaced with the screen which may, if desired, be provided with a bracket like 53 for connection with the stay.

50 In operating the latch member 55 its end 61 must be forced across the boss 62 which thus prevents accidental swinging movement of the latch such as might free the ear of the bracket. The end 57 of the latch member may be slightly 55 crimped or bent about a center line 63a so that it has a tendency to center itself in the groove 60 to further guard against accidental displacement of the parts.

The meeting ends of the arms 43 and 44 overlap to receive the center pivot bolt 45 and hard rubber or similar washers 64 are placed between these ends and between the head 65 of the bolt and the adjacent arm so that by drawing up the nut 66 adjustable tension or resistance may be provided at this joint as and for the purposes 65 previously described. The outer arm 44 has a flange 67 along one edge and the inner arm has an extended finger 68 adapted to engage an end of this flange to limit the unfolding action 70 of the arms as will be clearly evident.

Obviously by my invention a window stay may be disconnected at either end from the storm window, screen, or window frame, as may be desired, and this action may be carried out quickly and conveniently without the use of any tools.

It is understood that suitable modifications may be made in the structure as disclosed, provided such modifications come within the spirit and scope of the appended claims. Having now therefore fully illustrated and described my invention, what I claim to be new and desire to protect by Letters Patent is:

1. A window stay for detachable connection at one end to a window element, comprising an arm, a pin on the arm, a mounting plate secured to the window element and having a keyhole-shaped slot, the said pin being adapted for endwise entrance through the wider end of the slot and having a circumferential groove for pivotal engagement with the margins of the narrow end of the said slot, a spring secured to an inner side of the plate and extended at one end outwardly from the plate for manual operation, and a lug on the spring for engagement with the pin to prevent movement of the same from its pivotal engagement with the narrow end of the slot.

2. A window stay for detachable connection at one end to a window element, comprising an arm, a pin on the arm, a mounting plate secured to the window element and having a keyhole-shaped slot, the said pin being adapted for endwise entrance through the wider end of the slot and having a circumferential groove for pivotal engagement with the margins of the narrow end of the said slot, the said groove being spaced from the end of the pin to thereby provide a head portion on the pin which in use is disposed on the inner side of the plate, and a spring member secured to an inner side

5 35 of the plate and having means for releasably engaging the pin to prevent its displacement in the narrow end of the slot, the margins of the spring member being bent to engage the plate and cause the member to stand in spaced relation therewith sufficiently to substantially clear the head portion of the pin.
